Primary Examiner — Janice Hallmark*Assistant Examiner* — Adedoyin Taiwo O'Deyale(74) Attorney, Agent, or Firm — Fredrikson & Byron, P.A.(57) CLAIM

The ornamental design for a floating dispensing cartridge holder, as shown and described.

DESCRIPTION

FIG. 1 is a front perspective view of a floating dispensing cartridge holder showing our new design;

FIG. 2 is front side elevation thereof;

FIG. 3 is a left side elevation thereof;

FIG. 4 is a rear elevation view thereof;

FIG. 5 is a right side elevation thereof;

FIG. 6 is top plan view thereof; and,

FIG. 7 is a bottom plan view thereof.

The floating dispensing cartridge holder is for use in a spa or hot tub filter well.
